UNITED STATES PATENT OFFICE.

CHARLES H. SERGESON, OF PHILADELPHIA, PENNSYLVANIA.

ADJUSTABLE TENSION GUIDE FOR SHUTTLES.

Application filed January 6, 1927. Serial No. 159,321.

This invention relates to improvements in loom shuttles, and more particularly relates to improvements in the means for tensioning the yarn delivered by the shuttle.

5 The yarn-tensioning means, provided with shuttles of the type involved, ordinarily comprises a pair of opposed yarn-engaging elements between which the yarn passes, means being provided for resiliently holding 10 the elements together upon the yarn.

Due to the continuous frictional contact with the yarn, which is drawn between the tensioning elements, the latter become worn and require frequent replacement.

15 It is the principal object of the present invention to provide novel means for avoiding the necessity of these frequent replacements of the yarn-tensioning elements, and to this end, the invention contemplates the 20 provision of a novel form of yarn-engaging element, having means for relative adjustment thereof with respect to the yarn and to the opposed yarn-engaging element, whereby different parts of the element may be 25 brought into position to engage the yarn. Under these circumstances, when the aforesaid element becomes worn in one place, it may be adjusted to bring an unworn portion of the surface thereof into the yarn-engaging position.

30 In the attached drawings:

Fig. 1 is a plan view of one end of a shuttle made in accordance with my invention;

35 Fig. 2 is a section on the line 2—2, Fig. 1; and

Fig. 3 is a section on the line 3—3, Fig. 1.

Referring to the drawings, the shuttle comprises the usual body portion 1, having 40 therein a chamber 2 for reception of the yarn-cop, and having at one end of the chamber 2 a suitable tensioning device comprising, in the present instance, a pivotally mounted yarn-engaging element 3, and a 45 relatively fixed opposed yarn-engaging element 4. Suitable resilient means, such as a spring 5, is mounted in the shuttle so as to exert a pressure on the underside of the element 3, to resiliently hold the latter in an 50 elevated position against the underside of the element 4. It will readily be understood that the yarn, when passing out of the shuttle through an eyelet 6 in the bottom

of the latter, proceeds through a guide-eyelet 7 in the element 3 and between the latter 55 element and the opposed element 4.

The element 4 consists, in the present instance, of a cylindrical pin, extending transversely of the shuttle body, and having at one end a threaded part 8 of increased diameter which is mounted in a correspondingly threaded transverse passage 9 in the shuttle body. The other end of the pin 4 is slidably mounted in a transverse recess 10 in the said body. Suitable means is provided whereby the pin 4 may be turned to adjust its position in the loom, both longitudinally and angularly, and for this purpose I have provided the threaded extremity 65 with a slot 11 for the reception of a suitable tool.

In operation, the drawing of the yarn between the element 3 and the opposed element 4 has the effect of grooving and wearing the pin 4 to such an extent as rapidly to 75 render it unsuitable for the tensioning function. It is necessary, under these circumstances, to drive the usual form of pin from the shuttle and to replace it with a new pin, an operation frequently resulting in damage 80 to the body of the shuttle. In the present instance, the yarn, guided through one or the other of the eyelets 7 in the element 3, may be made to engage the pin 4 at a multitude of different positions on the latter by a 85 simple adjustment of the pin longitudinally, and by changing the angular position of the pin in the shuttle.

The device thus provides a simple and effective means for retaining the tensioning 90 device in perfect working condition, and avoids the necessity for frequent replacement of one of the tensioning elements.

I claim:

1. A yarn-tensioning device for loom-shuttles, comprising a pivotally mounted yarn-engaging element; an opposed yarn-engaging element in the form of a transverse pin; means for resiliently holding said elements together; and means for adjusting said pin both angularly and longitudinally in the shuttle, said pin being less in length than the width of the shuttle to permit longitudinal and axial adjustment of the pin without projecting beyond the faces of the 100 shuttle.

2. In a yarn-tensioning device for loom-shuttles, the combination with a pivoted yarn-engaging element, of an opposed yarn-engaging element in the form of a cylindrical pin threaded in the shuttle; resilient means for holding said pivoted element against the said pin; and means for turning

the pin on its axis to adjust it angularly and longitudinally in the shuttle, said pin being less in length than the width of the shuttle to permit longitudinal and axial adjustment of the pin without projecting beyond the faces of the shuttle. 10

CHARLES H. SERGESON.
